United States Patent Office

Des. 182,392
Patented Mar. 25, 1958

182,392

AUTOMOBILE

Richard M. Wagner, Warren, Mich., assignor to General
Motors Corporation, Detroit, Mich., a corporation of
Delaware

Application June 14, 1957, Serial No. 46,604

Term of patent 7 years

(Cl. D14—3)

Figure 1 is a rear elevational view of an automobile embodying my new design;

Figure 2 is a side elevational view;

Figure 3 is a sectional view taken on the plane indicated by line 3—3 of Figure 1;

Figure 4 is a sectional view taken on the plane indicated by line 4—4 of Figure 2;

Figure 5 is a top plan view with the center portion broken away for convenience of illustration.

Figure 6 is a perspective view.

The dominant features of my design reside in the portions shown in full lines.

I claim:

The ornamental design for an automobile, substantially as shown and described.
